UNITED STATES PATENT OFFICE.

OTTO W. SIEBERT, OF GARDNER, MASSACHUSETTS, ASSIGNOR TO O. W. SIEBERT COMPANY, OF GARDNER, MASSACHUSETTS, A CORPORATION OF MASSACHUSETTS.

CARRIAGE BODY.

Application filed July 12, 1926. Serial No. 121,772.

This invention relates to baby carriages or doll carriages or other similar articles of manufacture in which a portion of the article is provided with a covering of woven fibre reed.

This fibre reed is an artificial product made of strips of sheet material such as heavy kraft paper or other material having a strong fibrous nature. The strips are coated with gum or glue and are then twisted or folded under pressure to form either a round or a flat reed of very considerable strength and durability. Such reed may be readily woven into a flat fabric suitable for use as a covering for carriage bodies or chairs or other similar articles.

It is the object of my invention to utilize this woven fibre reed fabric to the greatest advantage in the covering of carriage bodies and other articles. In the attainment of this object, I so manipulate the material itself as to provide a stiffened edge portion which enables me to greatly simplify the frame structure of the article and to greatly reduce the cost of manufacture thereof.

My improved construction also provides a pleasing edge finish for the fabric.

My invention further relates to arrangements and combinations of parts which will be hereinafter described and more particularly pointed out in the appended claims.

Preferred forms of the invention are shown in the drawings in which—

Fig. 1 is a plan view of a carriage covering blank of woven fabric having the upper and lower edges stiffened and reinforced in accordance with my invention;

Fig. 2 is a sectional view, taken along the line 2—2 in Fig. 1;

Fig. 3 is a side elevation of a doll carriage body formed from the material shown in Fig. 1;

Fig. 4 is a detail sectional view, taken along the line 4—4 in Fig. 3;

Fig. 5 is a detail end elevation, looking in the direction of the arrow 5 in Fig. 3;

Fig. 6 is a detail sectional elevation of a slight modification;

Fig. 7 is a plan view of the carriage body shown in Fig. 3;

Fig. 8 is a side elevation of a modified form of body; and

Fig. 9 is a partial plan view thereof.

Referring particularly to Figs. 1 and 2, I have shown a piece of woven fibre reed 10

adapted to form the outer covering of a doll carriage. The fabric is first woven in a suitable loom in the usual manner and is produced in the form of a flat sheet of fabric. From this flat woven fabric a blank is cut 60 which may be of the shape shown in Fig. 1, and the upper or lower edges or both are then twice folded upon themselves, as indicated in Fig. 2, to form a double fold edge portion for the covering 10.

The provision of the double folds conceal the raw or unfinished cut edges of the woven fabric within the fold and provides a neat and attractive finished edge.

The edge portion thus provided is also of 70 very substantial strength and by providing such an edge portion, I am able to construct a baby carriage or doll carriage in the following very simple and inexpensive manner.

For this purpose, I provide a carriage bottom or frame member 12 to which the lower edge portion of the covering 10 is secured in any convenient manner, as by tacks or nails 13 (Fig. 3). Preferably I also provide a U-shaped metal binding member 15 for 80 the front edge portions of the attached covering 10.

One of these binding members is clamped over each front edge portion of the covering 10 after the latter is in place, and may be 85 secured to the bottom member 12 by a nail 16 (Fig. 3).

I also find it desirable to extend one side of the U-shaped member 15 in the form of an upward projection 17 and to fold this 90 projecting portion over the upper end of the member 15, securing it in position by a rivet 18 as indicated in Fig. 5. Any other suitable construction may be provided for binding the front edges of the covering 10. 95

The lower edge portion of the fabric may have the double fold indicated in Figs. 2 and 3, or the lower edge may be left straight and may be secured to the bottom member 12 by nailing a strip of braid or other covering material 20 over the straight lower edge of the fabric 10, (Fig. 6).

I have found that the double folded fibre fabric possesses in itself ample strength for the purpose intended, and that a baby carriage or doll carriage having the upper edge formed with the double fold shown in the drawings requires no additional upper frame members to secure it in position.

I am thus able to construct a baby or doll 110

carriage body at a very greatly reduced expense over the previous practice of providing a complete body frame to which the fabric was secured.

5 In Figs. 8 and 9, I have shown a slightly modified structure in which a sheet metal seat or bottom portion 25 is secured between curved wooden frame members 26. The lower edge 27 of the woven fibre 28 is 10 tacked or otherwise secured to the wooden frame members 26 and the curved edges are covered and protected by a covering strip 29 which may conveniently be formed from a piece of heavy reed or semi-circular cross 15 section.

The upper edge of the fabric 28 is provided with the double fold portion 30 as in the form previously described. This permits me to construct a body of a different 20 shape from that previously described while at the same time retaining the simplicity of frame construction and the economy attained by providing an upper edge portion which is entirely self-supporting.

25 While I have shown only a double fold at the edge of the fabric, it may be desirable to use three or more folds with lighter fabrics, all of which are within the scope of my invention and are intended to be included and 30 covered by the term "double fold" in the claims.

Having thus described my invention and the advantages thereof, I do not wish to be limited to the details of construction herein 35 shown and described, but what I claim is:

1. An article of manufacture having a covering of woven fibre reed and comprising a frame member and a covering therefor formed from a single continuous sheet of 40 woven fibre reed having one edge portion

thereof secured to said frame member and having an opposite edge portion twice folded upon itself to conceal the unfinished edge of the fabric and to provide an entirely self-supporting edge structure effective to 45 retain the adjacent portion of the covering in desired position.

2. A carriage body having a bottom portion, and a side covering for said body formed entirely of a single sheet of woven 50 fibre reed fabric secured at its lower edge portion to said bottom and having its upper edge supported and stiffened by the double folded integral edge portion of the woven reed fabric itself. 55

3. A carriage body having a bottom portion, and a side covering portion, said side portion comprising a single continuous sheet of woven fibre reed fabric with its lower edge firmly secured to said bottom portion 60 and having its upper edge formed solely of said woven reed fabric twice folded upon itself and forming an integral frame element effective in itself to support the upper edge portion of the side covering for said 65 body.

4. A carriage body having a bottom portion, and a side covering portion, said side portion comprising a single continuous sheet of woven fibre reed fabric with its lower 70 edge firmly secured to said bottom portion and having its upper edge twice folded outward upon itself to form a finished and stiffened upper edge effective in itself to support the adjacent portions of said side covering 75 in position.

In testimony whereof I have hereunto affixed my signature.

OTTO W. SIEBERT.
